ATTORNEYS

UNITED STATES PATENT OFFICE.

ELIAS LEWIS, OF TERRE HAUTE, INDIANA.

KNIFE.

Application filed April 15, 1922. Serial No. 552,888.

To all whom it may concern:

Be it known that I, ELIAS LEWIS, a citizen of the United States, and resident of Terre Haute, in the county of Vigo and State of Indiana, have invented certain new and useful Improvements in Knives, of which the following is a specification.

My invention relates to improvements in knives of the type of construction disclosed in Letters Patent of the United States #1,329,912 issued to me Feby. 3rd, 1920, and it consists in the combinations, constructions and arrangements herein described and claimed.

15 An object of my invention is to provide a knife of extremely simple construction which is adapted to hold a plurality of blades in such manner as to permit of the easy removal of a blade for sharpening or 20 replacement and equally as easy replacement of the blade in fully operative position.

A further object of my invention is to provide a knife which, as in the case of the knife disclosed in my aforesaid patent, is 25 adapted for use in marking, splitting, trimming and cutting operations, particularly with composition roofing, beaver board, leather, paste board, felt and the like, candy and as a pruning knife for trimming shrubbery, vines and the like.

30 A still further object of my invention is to provide a knife of the character described which will be extremely durable in the service for which intended.

35 Other objects and advantages will be apparent from the following description, and the novel features of the invention will be particularly outlined in the appended claims.

40 My invention is illustrated in the accompanying drawings, forming a part of this application, in which

Figure 1 is a side elevation of a knife embodying the invention in the form now preferred by me,

45 Figure 2 is an enlarged vertical longitudinal section through the knife exhibited in Figure 1,

Figure 3 is a section along the line 3—3 of Figure 2,

50 Figure 4 is a section along the line 4—4 of Figure 2,

Figure 5 is a side elevation of another embodiment of the same invention,

55 Figure 6 is a longitudinal vertical section through the knife shown in Figure 5,

Figure 7 is a section along the line 7—7 of Figure 6, and

Figure 8 is an enlarged plan view of a fragmentary portion of the structure shown in Figure 5.

In carrying out my invention in the form in which illustrated in Figures 1 to 4 inclusive, I provide a substantially U-shaped yoke or blade holder consisting of a web portion 1 and parallel arms 2, 2. The arms 65 2, 2 are arranged to straddle a longitudinal extension 3 at the forward end of a filler plate 4 which is disposed between the complementary longitudinal sections 5, 5 of a handle which is indicated generally at 6. 70

The sections 5, 5 of the handle are preferably made of wood while the filler plate and the yoke are preferably made of steel or other suitable metal. The lapped portions of the arms 2, 2 the filler plate 4 75 and the handle sections 5, 5 are secured together by transversely extending rivets 7 or the like. The arrangement is such that the extension 3 terminates at its outer end short of the web 1 of the yoke and extends 80 substantially along the longitudinal axis of the handle, being substantially flat and formed with straight side edges 8 and 9 respectively, which are spaced at their inner ends equi-distantly from the outer wall of 85 the handle, as best seen in Figures 2 and 3.

The numeral 10 denotes a sharp edged and sharp pointed blade for marking and trimming which is comprised in the embodiment of the invention now preferred by me, and 90 is provided with a laterally extending shank portion 11 which is adapted to be slidably received between the arms 2—2 of the yoke and to extend at its inner end between the complementary sections 5, 5 of the handle. 95 The rear side or edge of the shank portion 11 is adapted to lie flat against the edge 9 of the extension 3 for the greater part of its length, being beveled at its inner end, as indicated at 12. The second blade 13 100 which is a stub blade for cutting and splitting is arranged with the shank or body portion thereof extending between the web 1 of the yoke and the outer end of a slideable clamp bar 14. The body or shank of the 105 blade 13 is received at its extremity in a notch or cut away portion 15 in the extension 3 at the outer end of the latter. The clamp bar 14 has a length substantially equal to that of the tang portion 11 of the blade 110

10 and extends along the edge 8 of the extension 3 with the inner end thereof disposed between the complementary sections 5, 5 of the handle. The slidable clamp bar 14 is 5 beveled at its inner end, as at 15.

A locking ferrule 16 is rotatably mounted upon a reduced forward end portion 17 of the handle with one end thereof in abutting relation to the inner end of the filler plate 10, 4 and to a shoulder defined on the handle by the reduction of the portion 17 thereof. The locking ferrule 16 is provided with inclined or cam surfaces 18 and 19 upon its outer end and is arranged with these surfaces 15 respectively in engagement with a shoulder 20 provided on the outer edge of the slidable clamp bar 14 and a shoulder 21 provided on the blade 10. The arrangement is such that when the locking ferrule 16 is rotated 20 in one direction the blade 10 will be clamped against the web portion 1 and the blade 13 will likewise be clamped against the web portion 1 by the slidable bar 14. When the locking ferrule 16 is rotated in the opposite 25 direction, the blades 10 and 13 will be released and may be removed from the yoke or blade holder.

A blade 22 for cleaning the blades 10 and 13 is insertable through a slot 23 in an end plate 24 into a compartment 25 formed by providing a longitudinal aperture in the filler plate 4. The end plate 24 is apertured to receive stud projections 26, 26 which extend from the rear end of the filler plate 35 4 and are projected through the apertures of the end plate and upset, as at 27 to hold the end plate to the rear end of the handle.

From the foregoing description of the various parts of the device, the operation thereof may be readily understood. The blades 10 and 13 have their points and certain of their projecting edges sharpened so as to adapt these blades for use in the service for which intended. The blades can be removed readily and re-sharpened, when required, or replaced at small cost when worn to such an extent as to be unserviceable.

In the form of the device illustrated in Figures 5 to 8 inclusive, an extension 30 to the filler plate 4 extends from the forward end of the latter with its outer edge 31 in the plane of the corresponding edges of the arms 2, 2 of the yoke, thus providing a shoulder 32 at the juncture of the extension 30 and the filler plate 4. The shoulder 32 is in alignment with a shoulder 33 formed on the opposite edge of the filler plate 4 and in alignment with a shoulder 34 defined by reducing the forward end portion of the handle 55 6 to receive a locking ferrule 35. The latter therefore has its inner end abutting the shoulders 32 and 33 and the shoulder 34 of the handle. The outer end of the extension 30 terminates at an appreciable distance 60 85 from the web portion 1 of the yoke. The

locking ferrule 35 is formed to provide an inclined or cam surface 36 on its outer end which engages a shoulder 37 with which the marking and trimming blade 38 is provided.

The blade 38 has a body portion 39 received between the arms 2, 2 of the yoke. The body portion 39 is cut away at one corner, as indicated at 40 to receive the end of the body of a cutting and splitting blade 41. A lateral projection 42 of the blade 41 is adapted to enter a notch 43 in the wall of the cut-away portion of the body of the blade 38, whereby the blades 41 and 39 will be locked and both clamped against the web portion 1 when the locking ferrule 35 is 70 rotated in one direction. When the locking ferrule 35 is rotated in the opposite direction, the blade 38 may be moved away from the web portion 1 and both the blades 38 and 41 displaced from the yoke for sharpening or for any other purpose. A cap 44 is provided for the rear end of the handle 6 in the form of the device illustrated in Figures 5 to 8 inclusive. The filler plate 4 is secured to the handle and to the arms 2, 2 of the yoke by rivets 47 as in the preferred form of the device. The remaining parts of the form of the device illustrated in Figures 5 to 8 inclusive are precisely identical in essential respects with corresponding parts of the preferred form of the device, which has been described hereinbefore, and in consequence no description of these parts is deemed to be necessary herein. The same reference numerals have been used 90 to designate like parts of the several forms of the device illustrated in the drawings.

The operation of the form of the device illustrated in Figures 5 to 8 inclusive likewise is identical in essential respects with the 105 operation of the preferred form of the device and a description thereof is therefore deemed unnecessary herein.

Obviously, my invention is susceptible of embodiment in forms other than that in 110 which is illustrated in the accompanying drawings, and I therefore consider as my own all modifications and adaptations thereof of which fairly fall within the scope of the appended claims.

I claim:

1. A knife comprising a plurality of blades, a substantially U-shaped yoke having arms spaced apart to receive portions of the blades, a filler plate having an extension interposed between said arms, and spacing said blades apart, a handle overlapping the end portions of the arms of said yoke, means securing the handle, the filler plate and said yoke together, and means operable 120 to clamp said blades against the web of said yoke and to permit the release of said blades at will.

2. A knife of the character described comprising a filler plate having a bar like 130

extension at the forward end thereof, a substantially U-shaped yoke having arms straddling the extension and the forward end portion of the filler plate and having a web portion spaced from the end of the extension, a handle overlapping the filler plate and the end portions of the arms of the yoke, means for securing the handle, the filler plate and the arms of the yoke together, a marking and trimming blade having a body adapted to move between the arms of said yoke in sliding contact with one edge of said extension to the filler plate, said blade having a shoulder at its edge proximate to the handle, and the body thereof having a portion cut away at the edge thereof proximate to the web portion of the yoke, said cut-away portion having a notch formed in a wall thereof, a cutting and splitting blade having a body insertable between the end of the extension and the web of the yoke into the cut-away portion of the body of first blade and being provided with a projection adapted to enter the notch in the wall of the cut-away portion of the first blade, and a locking ferrule rotatably mounted upon the handle and having a cam surface engaging the shoulder of the first blade, whereby the said blades will be locked together and both held against the web of the yoke when the ferrule is rotated in one direction, and released when the ferrule is rotated in the opposite direction.

3. A knife of the character described comprising a filler plate having a bar like

extension at the forward end thereof, a substantially U-shaped yoke having arms straddling the extension and the forward end portion of the filler plate and having a web portion spaced from the end of the extension, a handle overlapping the filler plate and the end portions of the arms of the yoke, means for securing the handle, the filler plate and the arms of the yoke together, a marking and trimming blade, having a body adapted to move between the arms of said yoke in sliding contact with one edge of said extension to the filler plate, said blade having a shoulder at its edge proximate to the handle, and the body thereof having a portion cut-away at the edge thereof proximate to the web portion of the yoke, said cut-away portion having a notch formed in a wall thereof, a cutting and splitting blade having a body insertable between the end of the extension and the web of the yoke into the cut-away portion of the body of first blade and being provided with a projection adapted to enter the notch in the wall of the cut-away portion of the first blade, a locking ferrule rotatably mounted upon the handle and having a cam surface engaging the shoulder of the first blade, whereby the said blades will be locked together and both held against the web of the yoke when the ferrule is rotated in one direction, and released when the ferrule is rotated in the opposite direction, and a cap for the rear end of said handle.

ELIAS LEWIS.
